Attorney

UNITED STATES PATENT OFFICE.

FREDERICK H. TOWNSEND, OF BOSTON, MASSACHUSETTS.

HIDE-STRETCHING DEVICE.

1,355,928.

Specification of Letters Patent. Patented Oct. 19, 1920.

Application filed December 15, 1919. Serial No. 344,771.

To all whom it may concern:

Be it known that I, FREDERICK H. TOWNSEND, a citizen of the United States, residing at Boston, in the county of Suffolk and 5 State of Massachusetts, have invented an Improvement in Hide-Stretching Devices, of which the following description, in connection with the accompanying drawings, is a specification, like characters on the drawings representing like parts.

The invention to be hereinafter described, relates to devices for stretching hides and skins.

When the hides or leather have been 15 tanned and treated up to the point where they are intended for use in the manufacture of articles, it is customary to stretch the hide or leather while it is in a moist and pliable condition. This has the effect of increasing the area of the leather and at the 20 same time imparting to it pliability and evenness of texture.

One of the purposes of the present invention is to provide a simple, easily operated, 25 efficient frame for stretching hides or leather.

Another purpose of the invention is to provide a frame having adjustable members to which the hide may be tacked or secured, 30 and then the adjustable members may be adjusted relatively to the frame to stretch the hide both longitudinally and transversely thereof.

After the stretching frame has been in 35 use for a period, the stretching members or boards to which the hide is tacked, become so filled with tack holes that the tacks no longer obtain sufficient hold thereon. Another purpose of the invention, therefore, is 40 to provide a frame with stretching members which may be detachably associated with the frame, so that when they become filled with tack holes as described, new stretching members may be readily substituted therefor.

Another purpose of the invention is to provide a stretching frame having the characteristics referred to, and adapted to receive and stretch two hides or two hide portions simultaneously.

With the aforesaid and other objects in view, the character of the invention may be best understood by reference to the follow-

ing description of one good form thereof shown in the accompanying drawing, 55 wherein:

Figure 1 is a perspective view of a hide stretching frame embodying the invention;

Fig. 2 is a transverse section taken on line 2—2 of Fig. 1; 60

Fig. 3 is a perspective view of an edge portion of the frame; and

Fig. 4 is a sectional detail taken on line 4—4 of Fig. 1.

Referring to the drawing, the hide 65 stretching frame shown therein as one good form of the invention, comprises opposed pairs or groups of side members 1 of wood or other suitable material, and groups of end members 3, in the present instance, each 70 end group consisting of three members having their ends secured to the side members to form a frame of general rectangular character. The end members 3 may be spaced to receive the side members between them 75 to afford longitudinal guideways 5 and transverse guideways 7 for a purpose to be described. The upper pair of side members 1 may have end portions 9 projecting somewhat beyond the end members 7 and enable 80 the frame readily to be suspended on hooks to allow the hides to dry, as more fully hereinafter described. Extending between and transversely to the side members 1 is an intermediate member 11 permanently se- 85 cured thereto.

Before the hide is applied to the frame, it may be slotted longitudinally of the back thereof to form two sides of leather which may be mounted on opposite sides of the 90 frame and simultaneously stretched.

The leather may be tacked to opposed members for stretching the same transversely and to opposed members for stretching the same longitudinally. The members 95 for stretching the hide transversely, in the present instance, comprise a pair of members 13 of wood or other suitable material conveniently located adjacent and preferably within the upper side members 1. It 100 is desirable that these members shall be detachably associated with the frame and also that the tack-receiving faces of these members shall be practically free from nails, screws and similar securing means. To accomplish this, in the present instance, brack- 105

ets or strips 15 may be provided of metal or other suitable material extending between and transversely to the upper side members 1. These brackets or strips may be spaced 5 by blocks 17, and the brackets and blocks may be secured by screws 19 to the upper side members. The brackets may have outstanding flanges 21 for engagement with the outer edges of the upper side members 10 and the inner edges of the stretching members 13. The latter may be detachably secured to the transverse frame member 11 by screws 23. The construction is such that the members 13 may be mounted on the 15 brackets 15 and then secured by the screws 23. When the members 13 have become so filled with tack holes that it is desirable to substitute new ones therefor, it is merely necessary to remove the screws 23 to allow 20 the members 13 to be readily detached from the frame.

Opposed to and coöoperating with the fixed stretching members 13 are a pair of adjustable stretching members 25 of wood or 25 other suitable material, extending longitudinally of the frame and having end portions projecting into the guideways 7 between the end members 3 of the frame.

The back portions of the hide may be 30 tacked to the stretching members 13, and the belly portions of the hide may be tacked to the adjustable stretching members 25. Then the latter may be slid transversely of the frame away from the fixed stretching 35 members 13 to stretch the hide transversely thereof as desired.

Suitable means may be provided to secure the stretching members 25 in their positions of adjustment. To accomplish this, in the 40 present instance, the end members 3 of the frame may be provided with series of holes 27 conveniently arranged in rows in staggered relation, and pins 29 may be inserted in these holes and engage the inner edges 45 of the stretching members 25 to hold the same in their positions of adjustment.

The members for stretching the leather longitudinally thereof, in the present instance, comprise a pair of members 31 of 50 wood or other suitable material extending transversely of the frame through the guideways 5 between the side members 1 of the frame. These stretching members 31 may project somewhat beyond the side members 55 of the frame, and have blocks 33 secured thereto with inner curved edges or rockers for engagement with the outer edges of the side members 1 of the frame, thereby allowing the stretching members 31 to be adjusted longitudinally of the frame, and to rock 60 or depart from positions truly perpendicular to said side members as desired.

The end portions of the leather may be tacked to the end stretching members 31, 65 and then the latter or one of them may be

adjusted longitudinally of the frame to stretch the leather longitudinally the degree desired.

Suitable means may be provided for securing the end stretching members 31 in their positions of adjustment. To accomplish this, in the present instance, the side members 1 of the frame may be provided with series of holes 35 conveniently arranged in rows in staggered relation, and adapted 75 to receive pins 37 which may be set in the holes to engage the inner edges of the end stretching members 31 to hold the same in their positions of adjustment as required.

After the stretching members 31 have been 80 used for a period, they will become so filled with tack holes that it will be desirable to substitute new ones therefor. To accomplish this, the blocks 33 at one of the ends of each of said members may be removed 85 and thereby allow the members to be withdrawn from the frame transversely thereof. Then new members may be readily inserted into the frame through the guideways 5, and the blocks 33 may be applied thereto to prevent 90 their withdrawal from the frame.

The use of the frame in stretching leather will be readily understood. The back and belly of the hide are tacked to the side stretching members 13 and 25, and the ends 95 of the hide are tacked to the end stretching members 31, and then the frame may be reversed, and a hide may be tacked to the side stretching members at the opposite side of the frame and to the end stretching members. Then the side stretching members 25 may be adjusted and held by the pins 29 to 100 stretch the leather transversely as required, and the end stretching members 31 may be adjusted and held by the pins 37 to stretch 105 the leather longitudinally as desired. After the hides have been secured to the opposite sides of the frame and stretched, the frame may be suspended by resting the end portions 9 of the upper side members of the 110 frame on hooks or any suitable support.

When the side stretching members and the end stretching members become so filled with tack holes that others should be substituted therefor, this may be readily accomplished 115 by removing the members 13 and 31 as described. The members 25 may be removed readily by sliding them out through the guideways 7.

It will be understood that the invention is 120 not limited to the specific embodiment shown, and that various deviations may be made therefrom without departing from the spirit and scope of the appended claims.

What is claimed is:—

1. A device for stretching two hides simultaneously, comprising a frame having side members and end members connected to said side members; a pair of adjacent fixed side stretching members, a pair of inde- 130

- pendently adjustable side stretching members adapted to slide between said end members toward or from said fixed stretching members, a pair of end stretching members 5 adapted to slide between the side members of said frame, and means to secure said 10 stretchable members in different positions of adjustment.
2. A device for stretching hides, comprising a frame having groups of side members and end members spaced to afford guideways between them, a pair of side stretching members 15 stretchable in the guideways between the end members, a pair of fixed side stretching members opposed to said stretchable side stretching members, end stretching members stretchable in the guideways between the side members, and means to hold 20 said stretchable side and end stretching members in different positions of adjustment.
3. A device for stretching leather, comprising a frame having opposed side members and opposed end members connected to said side members, a pair of brackets secured to one of the side members of the 25 frame, a fixed stretching member resting on said brackets and retained by the brackets against displacement by stretching strains, means detachably to secure said fixed member to the frame, an adjustable stretching member mounted on the frame and opposed to said fixed member, and means coöperating with the frame and adjustable stretching member for holding the 30 latter in different positions of adjustment.
4. A device for stretching leather, comprising a frame having transverse guideways, a pair of fixed stretching members mounted on the frame, a pair of longitudinal stretching members opposite the 35 respective fixed members and stretchable in said transverse guideways, and means to hold said stretchable stretching members in different positions of adjustment.
5. A device for stretching leather, comprising a frame having longitudinal and transverse guideways, and means for stretching leather on opposite sides of said frame including a pair of fixed stretching members, a pair of independently adjustable 40 stretching members opposite the respective fixed members and stretchable in said transverse guideways, a pair of stretching 45

members stretchable in said longitudinal guideways, and means to secure said stretchable members in different positions of adjustment. 55

6. A device for stretching leather, comprising a frame having opposed side members spaced to form guideways therebetween, opposed end members connected to said side members, adjustable stretching members projecting through said guideways beyond said side members, and elements connected to said stretching members 60 and adapted to engage edges of said side members to limit longitudinal movement of said stretching members and allow a rocking adjustment thereof. 65

7. A device for stretching hides simultaneously upon the opposite sides of a frame, comprising a frame having transverse guideways, a pair of fixed stretching members, a pair of independently adjustable stretching members stretchable in said transverse guideways and arranged opposite the respective fixed members, means for securing the adjustable slide members in different positions of adjustment, and means for stretching the ends of the hides. 70 75

8. A device for stretching hides simultaneously upon the opposite sides of a frame, comprising a frame having longitudinal and transverse guideways, a pair of fixed stretching members, a pair of independently adjustable stretching members stretchable in the transverse guideways and arranged opposite the respective fixed members, means for securing the adjustable slide members in different positions of adjustment, and stretching members stretchably mounted in the longitudinal guideways to 80 stretch the ends of the hides. 85

9. A device for stretching hides, comprising a hollow frame having longitudinal and transverse guideways, a fixed stretching member, an adjustable stretching member stretchable in the transverse guideways and arranged opposite the fixed member, stretching members stretchably mounted in the longitudinal guideways, and means for retaining the stretching members in different positions of adjustment. 90 95 100

In testimony whereof, I have signed my name to this specification.

FREDERICK H. TOWNSEND.
